UNITED STATES PATENT OFFICE.

EDWIN S. FLARSHEIM AND JOHN G. H. LIEBEL, OF CINCINNATI, OHIO.

BUCKEY DIAPHRAGM FOR SCATTERED X-RAY RADIATION AND PROCESS OF MAKING THE SAME.

Application filed March 6, 1924. Serial No. 697,341.

To all whom it may concern:

Be it known that we, EDWIN S. FLARSHEIM and JOHN G. H. LIEBEL, citizens of the United States, and residing at Cincinnati, in the county of Hamilton and State of Ohio, have invented a new and useful Buckey Diaphragm for Scattered X-Ray Radiation and Processes of Making the Same, of which the following specification is a full disclosure.

This invention relates to an improved diaphragm or grid used in röntgenography of X-ray photography and to the process of making the same, and particularly to a type in which the grid is composed of longitudinal strips of material, impermeable and permeable for Röntgen rays in alternate arrangement side by side with the adjacent walls of the strips parallel and unidirectional, and the impermeable strip in lines radiating from a common center at the anode of the Röntgen tube. Commercially grids of this character are generally made to give a spherical shape or grid surface, as a most practical form of manufacture in that strips of uniform cross section can be employed facilitating assembling, although a plane form is more preferable. The plane form provides for the use of a flat table upon which the object or patient can be more advantageously positioned, and likewise permits the table, grid and sensitized photographic plate or film to be sustained in parallelism, productive of more efficient results and offering greater convenience in manipulation.

To produce a plane form of grid with the impermeable strips theoretically all in radial lines with a common axis or relatively different angularly disposed to produce such an arrangement has heretofore not been found feasible for commercial production, as the side walls of each permeable strip between the impermeable strips would have to be of different angles from one another, rendering the production of the grid tedious and costly.

The present invention provides for an economical and practical commercial production of a plane grid composed of groups of strip units or sections of grid, in which the strips of each group or section permeable and impermeable for Röntgen rays are plane strips in parallel arrangement side by side, with the strips of one section disposed at an angle to the strips of another section, and rela-

tively in approximate radiating lines from a common center.

Aside from the construction of the grid as an article of commerce it is also an object of the invention to provide for a simple and expedient method of making the same and particularly the sections thereof which will avoid handling the strips individually for assembling.

Further features and advantages of the invention will be more fully set forth in the description of the accompanying drawings forming a part of this specification, in which:

Figure 1 is a diagrammatic and longitudinal section of a portion of an X-ray apparatus.

Figure 2 is a section on line 2—2, of Fig. 1.

Figure 3 is an enlarged sectional view of a portion of the grid, and

Figure 4 is an enlarged sectional view of two sections or groups of strip units of the grid.

Referring to the drawings, 1 indicates the table of the X-ray apparatus upon which the object or patient undergoing examination rests, and beneath the table a frame structure 2 is appropriately mounted for supporting the carriage 3, carrying the grid 5. The carriage is provided with rollers 4 engaged upon the tracks 6—6 adapting the carriage to be freely translated longitudinally beneath the table. The grid therefore is movably mounted and is provided with mechanism not shown for imparting motion to the same when the photograph is taken or making an exposure. Beneath the grid a plate or film holder 7 is removably mounted. The carriage mechanism and plate or film holder devices may be of any conventional form.

The commercial X-ray apparatus, usually, is provided with controlling devices for either manual or automatic control of the electric circuits and moving parts, but as the present invention deals only with the construction of the grid or screen and the process of making the same, it is deemed that the general reference to and disclosure of an X-ray apparatus as made herein is sufficient for the present purposes. Likewise as the objects and purposes of a grid of this character are well known in the art, as primarily to nullify or prevent the injurious effect of secondary or scattered rays on the photographic plate, no enlargement thereof will

be made herein except to note that the grid is preferably of the type having a thin strip impermeable for Röntgen rays extending longitudinally for the full width of the grid, 5 as a most approved form and distinguished from the cellular form.

The grid structure therefore is composed of a number of wood and lead strips 8 and 9 respectively, in alternate arrangement side 10 by side, adhesively and compressively secured together into a unit, the unit having plane upper and lower or opposite face side surfaces, with the lead strips disposed at an angle to one another, or in radial lines to a 15 common axis or focusing point. Both the wood and lead strips individually represent plane parallel sided lengths of materials, all the wood strips and the lead strips respectively being of same dimension, with the 20 lead strips of relatively smaller gauge thickness than the wood strips. The strips in their alternate arrangement for the grid are combined in groups or grid sections, with the strips which make up each group or section 25 in parallelism and relatively at an angle to the strips of a second or adjoining group or grid section.

The strip groups or grid sections are strip widths cut from a laminated board, the 30 board being built up of a definite number of sheets of wood and lead material, as permeable and impermeable material for Röntgen rays, the different material sheets in alternate arrangement being laid one upon 35 the other and adhesively united to form a composite board. This composite board, with the sheets or layers in horizontal position is cross cut into strip width, designated as grid sections. The cut sides of the grid 40 sections being the upper and lower face surfaces of the grid when the sections are secured together. The laminations thus are transposed from the horizontal position on the board to a vertical position for the grid 45 when the sections in building up the grid are placed side by side. In cross cutting the composite board the degree of cutting angle is changed for each strip width or grid section, for establishing a progressive order of 50 inclination of the lead strip when the grid sections are assembled, this being for the purpose of positioning the lead strips of the various sections at relative approximate angles, corresponding appropriately to 55 radial lines from a common focusing axis or point for the grid. The several sections of a number required for a given size of grid assembled in a definite order, at opposite sides of a central grid section, to bring the 60 lead strips of the sections on one side of the central grid section in an opposite direction from those at the opposite side of the central grid section, are adhesively cemented together and placed in a die or holder for 65 compressing the same together and uniting

the sections into a single unit, the compression uniting the sections so that no fillet is required between adjoining sections to accommodate for any spacing between the sections due to the relatively different angles of the opposing sides of two adjacent sections. After the sections have been joined together and the unit removed from the die the upper and lower surface may be dressed or finished as desired. The grid thus 70 formed comprises a series of flat wood and lead strips divided into groups or sections, with the lead strips in one group in parallelism, and at an angle to the parallel strip of second adjoining group and all of the lead 75 strips, occupying an appropriate position to approximately present the same in radial lines with a common focusing axis or point for the grid. The parallelism of the lead strips of the different sections, owing to the 80 limited number employed for each section appear to be of advantage in a moving grid, as presenting a minimum interference with the primary rays. The shifting movement of the grid progressively center the lead 85 strips with the focusing point, so that the same are moved into radial lines with the focusing point while others are slightly deviated therefrom establishing an equalization 90 for the production of a very clear and sharply defined negative. It is obvious that the grid plate could be made of rectangular instead of parallelogramic sections and before permanently set could be given a spherical form if desired. 95

Having described my invention, I claim:

1. A grid for X-ray photography comprising a plate composed of parallel sided strips of different material permeable and impermeable for Röntgen rays secured together side by side in alternate arrangement. 105

2. A grid for X-ray photography comprising a composite plate composed of sections united together, each section having parallel strips of material impermeable for Röntgen rays secured together with intervening strip of material permeable for Röntgen rays and the ray impermeable strips of one section disposed at an angle to the corresponding strips of an adjoining section. 110

3. A grid for X-ray photography, comprising a composite plate composed of sections secured together, each section comprising parallel laminations of different material in alternate arrangement, and the sections secured together with the laminations of one section at an angle to the laminations of an adjoining section. 120

4. The process of making a grid for X-ray photography which consists in forming a composite board of laminations of different material, relatively permeable and impermeable for Röntgen rays in alternate arrangement, cross cutting the board into grid 125 130

sections and securing the sections together to form a plate with the cut edges of the sections forming the face surface of the plate.

5. The process of making a grid for X-ray photography which consists in forming a composite board of laminations of different material, relatively permeable and impermeable for Röntgen rays in alternate arrangement, cross cutting the board into grid sections, securing the sections together to form a plate with the cut edges of the

sections forming the face surface of the plate, and with the laminations of one section at an angle to the laminations of an adjoining section. 15

In witness whereof, we hereunto subscribe our names, as attested by the two subscribing witnesses.
